BIRNEY C. BATCHELLER, OF WALLINGFORD, VERMONT, ASSIGNOR TO THE LAMSON COMPANY, OF SYRACUSE, NEW YORK, A CORPORATION OF MASSACHUSETTS

PNEUMATIC DESPATCH SYSTEM

Application filed November 1, 1928. Serial No. 316,391.

This invention pertains to pneumatic despatch systems and more particularly to means for automatically starting and stopping the flow of air in a pneumatic tube line. In order to economize power in the operation of a pneumatic despatch system it is desirable to cut off the air flow through the tube line when the latter is idle, that is to say, when no carriers are passing through it. Various devices have been proposed for accomplishing this result. In some arrangements the air flow is cut off or short circuited by actuation of a valve, while in others the blower fan or other air impelling means is stopped and started at the proper times. The automatic control of such a valve or of the air impelling means, has been accomplished in many ways as, for example, by the action of detectors responsive to differences in pressure in or velocity of the air in the tube line, or by the operation of parts mechanically or electrically actuated by the carrier as the latter enters or emerges from the tube. While many such automatically controlled devices are theoretically operative, it is found in practice that some of these devices, at least, are so delicate in operation, and complex in construction as to require constant attention for adjustment or repair, while devices of this character are often expensive to build and install.

In the operation of a pneumatic tube system it is customary to assign to each sending station a certain number of carriers which, after being despatched from the station, are ultimately returned to the sending point, and in accordance with the present invention I take advantage of this fact and provide simple, reliable, and relatively inexpensive means which responds to the presence of a carrier, or a predetermined number of carriers at a given station, to cut off the air flow through the system as, for example, by stopping the power driven air impelling fan blower or the like, such means likewise responding to removal of a carrier, or a selected number of carriers from the sending station to initiate operation of the power driven air impelling means.

This responsive means may, if desired, be

arranged to cut off the air flow immediately upon delivery of a returning carrier to the station or, alternatively, after the arriving carrier has been picked up by the operator and placed in its usual idle position. The responsive means may, if desired, be sensitive to the mere presence of a carrier in normal idle position; to a particular disposition of the idle carrier, for example, horizontal or vertical; to special configuration of a carrier; to the weight of the carrier, or in fact, to any other desired characteristic.

For convenience in illustration I have chosen to disclose an embodiment of the invention wherein the removal of a carrier from normal idle position results in closing an electrical circuit whereby the power driven fan or blower is started, but the invention is not necessarily limited to such embodiment or the employment of electrical devices, since in its broader aspects pneumatic or mechanical connections may control the operation of the power driven means.

Preferably I provide signal means, for example, a lamp which is lighted as soon as the air impelling means is set into operation, thus indicating to the operator that the system is in operative condition ready for the despatch of a carrier, and at the same time warning the operator if, for any reason, the air impelling device remains in operation too long.

In the accompanying drawings I have illustrated certain desirable embodiments of the invention by way of example, and in the drawings;

Fig. 1 is a diagrammatic side elevation, partly in section and to small scale, showing desirable embodiments of the improved control device installed at stations connected by a pneumatic tube line;

Fig. 2 is a plan view, to larger scale, more or less diagrammatic in character, illustrating one form of control device which may be employed;

Fig. 3 is a vertical section, of more or less diagrammatic character, taken on the line 3-3 of Fig. 2;

Fig. 4 is a view similar to Fig. 3 but showing another form of control device;

Fig. 5 is a diagrammatic side elevation, partly in section, showing another form of the control apparatus arranged to respond directly to the arrival of carriers at the delivery terminal; and

Fig. 6 is a vertical section, to larger scale, showing details of a slightly modified control device of the general type illustrated in Fig. 5.

Referring to the drawings, the numerals 1 and 2 designate, respectively, fragmentary portions of desks or other suitable means to support the terminal devices of a pneumatic despatch system. The parts 1 and 2 are disposed at spaced stations of such a system, for example, the central station and a remote sending station of a store service line, although the invention is not in any way limited to the character of the transactions performed by the pneumatic despatch system or to the character of the stations at which the terminals are arranged.

A tube 3 having a despatch terminal 4 leads from the station 1 to a delivery terminal 5 at the station 2 and at the latter station a despatch terminal 5^a gives access to a return tube 6 having a delivery terminal 7 at the station 1. An extension 8 of the tube 6 leads to an exhaust blower 9 driven by an electric motor 10. This motor receives electrical energy from power lines 11 and 12 and is controlled by means of a magnetic switch 13 of known type.

Suitable receptacles 14 and 15, for example boxes or baskets, are arranged beneath the delivery terminals 5 and 7 respectively to receive the carriers discharged therefrom. In accordance with the present invention, either or both of the receptacles 14 and 15 may be of a special type hereinafter more fully described.

At one of the stations, for example the station 2, I provide a holder or receptacle 16 for the reception of the idle carriers. This receptacle may be designed to hold a single carrier or a plurality of carriers as preferred. As here disclosed (Fig. 2) the receptacle 16 has a plurality of compartments 16^a, each adapted to hold a single carrier disposed substantially vertically. The receptacle 16 (Figs. 2 and 3) is provided with a bracket 18 corresponding to each compartment 16^a, and each bracket supports a lever 19. The compartments 16^a are open at their bottoms and each lever 19 has an arm 20 disposed at the lower end of the corresponding compartment 16^a in such a position as to form a support for a carrier 17 within the compartment. Each lever 19 is provided with an outstanding arm having an electrical contact 21 which is adapted at times to engage a complementary contact 22. The contacts 21 and 22 are connected to wires 24 and 23 respectively, and these wires lead to the magnetic switch 13, the latter being so designed that when the contacts

21 and 22 engage each other, thereby completing an electrical circuit, the switch 13 operates and causes the motor 10 to start. Normally, when a carrier 17 rests upon the arm 20 of the lever 19, the arm 20 is depressed, thus raising the contact 21 out of engagement with the contact 22 and breaking the circuit. As here shown, the lever 19 is provided with an adjustable weight 25 which tends to swing the lever so as to bring the contact 21 into engagement with the contact 22, but in place of a weight it is obvious that a suitable spring may be provided. Preferably a stop 26 is disposed beneath the arm 20 of the lever to prevent undue downward movement of the latter when a carrier is placed in the compartment. With this arrangement the weight of the carrier in the receptacle keeps the contacts 21 and 22 separated, but when the carrier is removed from the receptacle, the contacts automatically engage, thus completing the circuit and causing the motor to start.

While the type of receptacle just described may be employed at both stations, I may, if desired, employ a different type of receptacle at the station 1, as shown for example in detail in Fig. 4. This second type of receptacle 28 is provided with one or more compartments 29 in the same way as the receptacle 16, but in this instance these compartments are closed at their lower ends. The receptacle supports a pivoted lever 31 corresponding to each compartment 29, each lever having an arm 32 adapted to project through a slot 33 in the side of the receptacle and to be engaged by a carrier 30 disposed within the compartment. Each lever 31 carries a contact 34 adapted to engage a contact 35 to close a circuit through wires 36 and 37 which are connected to the wires 23 and 24 respectively. The levers 31 may be counterweighted in the same way as the levers 19, or may be provided with springs, if preferred. Normally these levers tend to swing so as to project their arms 32 into the compartments in the receptacle and to cause their contacts 34 to engage with the corresponding contacts 35. When a carrier 30 is placed in a compartment, the lever arm is pushed out and held in this position so long as the carrier remains in the compartment and while so positioned the contact 34 is spaced from the contact 35. When the carrier is removed the circuit is closed through the switch 13 and the motor 10 is started.

If desired the receptacles 14 and 15 which receive the carriers discharged from the respective delivery terminals may be of another type as disclosed in detail in Figs. 5 and 6. Thus in Fig. 5 the receptacle 14 is of box-like character and adapted to hold several carriers and is placed immediately below the delivery terminal 5. The receptacle 14 has a false bottom 39 which is hinged at 40 and which is urged to swing upwardly by

means of a spring 41. A pin projects downwardly from a bottom member 39 and is provided at its lower end with a metallic plug 42 which is adapted, when the bottom member 39 swings upwardly, to engage a pair of spaced resilient contacts 43 and 44, and thus to complete an electrical circuit through wires 45 and 46 connected to the wires 23 and 24 above described. The spring 41 is of such strength that when a selected number of carriers, for example four, as here shown, is disposed within the receptacle 14, the weight of such carriers holds the bottom member 39 down so that the plug 42 does not engage the contacts 43 and 44. Whenever a carrier is removed from the receptacle, the spring 41 elevates the member 39 thus completing the circuit through the switch 13 and causing the motor 10 to start into operation. When the carrier thus removed from the receptacle 14 has been despatched to the station 1 and returned through the tube 3 it is delivered through the terminal 5 into the receptacle 14 and unless other carriers have previously been removed the weight of the arriving carrier immediately depresses the member 39, thus breaking the circuit and causing the motor to stop.

In Fig. 6 a slightly different construction is shown, wherein the bottom member 39 of the receptacle 14 rests upon a vertically sliding pin 49 mounted in an insulating bushing 50. A spring 51 tends to elevate the member 39. The pin 49 is provided with a shank portion 52, preferably of smaller diameter, carrying a metallic plug 53, adapted when the pin is elevated, to engage a pair of spring contacts 54 and 55, and thus to close the circuit through the wires 45 and 46. Normally when a full complement of carriers is within the receptacle 14, the member 39 is depressed to the dotted line position where the plug 53 no longer engages the contacts 54 and 55, but when one or more carriers are removed from the receptacle the member 39 raises, the circuit is completed and the magnetic switch 13 causes the motor 10 to start.

Preferably at each station I provide a signal device, as for example, the lamps 29 and 38, respectively, connected by suitable wiring to the magnetic switch 13, the latter being so designed that whenever it is energized to close the motor circuit, it also closes a circuit through the signal devices. Thus so long as the motor is in operation the signal lamps, or other devices are energized,—indicating to the operator that power is being used.

Preferably the wires leading from the several receptacles 14, 16, 28, etc., are provided with controlling switches 47, 48, and 37^a respectively, so that if desired any of these devices may be rendered temporarily inoperative. Thus, for example, at the station 2, either or both of the receptacles 14 and 16

may be used as desired. When both of these receptacles are employed a predetermined complement of carriers is assigned to each receptacle. If now a carrier be removed from a receptacle 14, the motor will be started into operation and will remain in operation until such carrier has been restored to the receptacle 14, the restoration of the carrier to the receptacle being dependent in this instance only upon its delivery from the terminal 5. On the other hand, if a carrier be removed from a receptacle 16, the return of such carrier to the receptacle 14 will have no effect upon the operation of the motor, which will continue to run until the operator has picked up the carrier and manually restored it to the receptacle 16. If more than one carrier be removed from a given station and transmitted through the line, the motor will continue to operate until the entire number of carriers thus removed and despatched has been returned to the sending station and restored to the receptacle from which it was taken. Since the several types of receptacles herein described are of generally interchangeable character, it is possible to use one or more types at each station in accordance with the requirements of each individual installation, and while I have herein disclosed certain desirable embodiments of controlling means, I wish it to be understood that the invention is not necessarily limited to the precise details herein disclosed, but that changes in shape, size and arrangement of parts as well as the substitution of equivalents may be made without departing from the spirit of the invention.

I claim:—

1. Power control apparatus for use with a pneumatic tube line extending between two stations and having power driven means for creating a carrier impelling air flow in said line, said apparatus comprising a receptacle capable of holding a plurality of carriers, a movable part in the receptacle which remains in one position so long as a predetermined number of carriers are within the receptacle, means operative to raise said part upon reduction of the number of carriers in the receptacle below such predetermined number, and means responsive to such upward movement of said part for starting the power driven means into operation.

2. Power control apparatus for use with a pneumatic despatch system having spaced stations, a tube line connecting them, and means for creating carrier impelling air flow in said line, said tube line having a delivery terminal at one station at least, a receptacle into which carriers arriving through said terminal are delivered and come to rest, and means responsive to the weight of a predetermined number of carriers in said receptacle for stopping carrier impelling air flow in the line, said means remaining inoperative

so long as less than such predetermined number of carriers is in the receptacle.

3. Power control apparatus for use with a pneumatic tube line extending between two stations and having power driven means for creating a carrier impelling air flow in said line, said apparatus comprising means responsive to the removal of a carrier from a predetermined idle position at one of said stations for actuating a signal device.

4. Power control apparatus for use with a pneumatic tube line extending between two stations and having power driven means for creating a carrier impelling air flow in said line, said apparatus comprising means for actuating a signal device so long as said power driven means is in operation.

5. Power control apparatus for use with a pneumatic tube line extending between two stations and having power driven means for creating a carrier impelling air flow in said line, said apparatus comprising means for actuating a signal device so long as a carrier impelling air current flows in the line.

25 6. Power control apparatus for use with a pneumatic tube line extending between two stations and having power driven means for creating a carrier impelling air flow in said line, said apparatus comprising means responsive to removal of a carrier from a predetermined idle position at one of said stations for simultaneously starting said power actuated means and actuating a signal device.

35 7. Power control apparatus for use with a pneumatic tube line extending between two stations and having power driven means for creating a carrier impelling air flow in said line, said apparatus comprising a receptacle capable of holding a plurality of carriers, a movable part in the receptacle upon which the plurality of carriers rest, a predetermined number of such carriers moving said part into one position, means operative when less than the predetermined number of carriers are in the receptacle to move the part into another position, and means responsive to said last movement for starting the operation of the power driven means.

50 8. Power control apparatus for use with a pneumatic tube line extending between two stations and having power driven means for creating a carrier impelling air flow in said line, said apparatus comprising a receptacle capable of holding a plurality of carriers, a movable false bottom in the receptacle upon which the plurality of carriers rest, a predetermined number of carriers moving the false bottom into one position, means operative when less than the predetermined number of carriers are in the receptacle to move the false bottom into another position and means responsive to said last movement for starting the operation of the power driven means.

65 9. Power control apparatus for use with a pneumatic tube line extending between two

stations and having power driven means for creating a carrier impelling air flow in said line, said apparatus comprising a receptacle capable of holding a plurality of carriers, a false bottom hinged in the receptacle upon which the plurality of carriers rest, a predetermined number of carriers swinging the false bottom on its hinges into one position, a spring normally opposing such movement of the false bottom and operative, when less than the predetermined number of carriers are in the receptacle, to swing the false bottom into another position and means responsive to said last movement for starting the operation of the power driven means.

70 10. Power control apparatus for use with a pneumatic despatch system having spaced stations and a pneumatic tube line extending between two stations, comprising mechanism for creating a carrier impelling air flow in said line, a delivery terminal in said tube line at one station at least, a receptacle into which carriers arriving through said terminal are delivered, and means for starting and stopping the operation of the flow creating mechanism, said means being responsive to the removal of a carrier from the receptacle for starting such operation.

75 11. Power control apparatus for use with a pneumatic despatch system having spaced stations and a pneumatic tube line extending between two stations, comprising mechanism for creating a carrier impelling air flow in said line, a delivery terminal in said tube line at one station at least, a receptacle into which carriers arriving through said terminal are delivered, and means for starting and stopping the operation of the flow creating mechanism, said means being responsive to the removal of a carrier from the receptacle for starting such operation and responsive to the delivery of a carrier to the receptacle for stopping such operation.

80 12. Power control apparatus for use with a pneumatic despatch system having spaced stations and a pneumatic tube line extending between two stations, comprising mechanism for creating a carrier impelling air flow in said line, a delivery terminal in said tube line at one station at least, a receptacle into which carriers arriving through said terminal are delivered, a signal device, and means for controlling said device and for starting and stopping the operation of the flow creating mechanism, said means being responsive to the removal of a carrier from the receptacle for starting said signal device and such operation.

85 13. Power control apparatus for use with a pneumatic despatch system having spaced stations and a pneumatic tube line extending between two stations, comprising mechanism for creating a carrier impelling air flow in said line, a delivery terminal in said tube line at one station at least, a receptacle into which carriers arriving through said terminal are
